(57) **CLAIM**

The ornamental design for an “intra-oral scanner handle”, as shown and described.

DESCRIPTION

FIG. 1 is a perspective view of an intra-oral scanner handle; FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom view thereof.

The broken line showing of portions of the “intra-oral scanner handle” is included for the purpose of illustrating environmental structure and forms no part of the claimed design.
